PRODUCTION OF KNITTED FABRICS

Albert Fairholme Guyler and William Henry Boaler, Spondon, near Derby, England, assignors to Celanese Corporation of America, a corporation of Delaware

Original application November 28, 1939, Serial No. 306,476. Divided and this application August 27, 1941, Serial No. 408,450. In Great Britain November 29, 1938

10 Claims. (Cl. 66—190)

This invention relates to knitted fabrics, and is especially concerned with a knitted fabric having a high degree of elasticity by reason of a content therein of elastic yarn. The application is a divisional of U. S. application Serial No. 306,476, filed November 28, 1939. It is an object of the present invention to provide a fabric that is knitted on a circular knitting machine and possesses a substantial degree of elasticity both in the direction of the courses of the fabric and in the direction of the wales.

According to the present invention a circular knit elastic fabric comprises a plurality of inelastic yarns knitted into loops to form wales and continuous helical courses, and at least one elastic yarn laid into the fabric at the intersections of selected wales with one of said courses and laid into the fabric at the intersections of other selected wales with another of said courses spaced from the first, the parts of said elastic yarn lying between said courses, besides proceeding always in the same direction circumferentially of the fabric, extending always in one direction longitudinally of the fabric from one of said courses and always in the other direction from the other of said courses. By laying in an elastic yarn in this manner the fabric is given an elasticity, due to contraction of the elastic yarn and this elasticity appears not only in the direction of the courses but also in the direction of the wales of the fabric by reason of the fact that the elastic yarn, between the different points at which it is laid in, extends over several courses.

For the purpose of feeding and laying in the elastic yarn the method and machine described in the parent application, Serial No. 306,476, filed November 28, 1939, may be employed. As more particularly described in that application, suitable elements may be provided to which the elastic yarn is fed under tension, the elements being subsequently moved so as to bring the elastic yarn in front of the needle, so that as the needle rises the yarn may slip below the beard or latch thereof in order to lay the elastic yarn into the fabric. The elements, however, will not work all at once, certain of them presenting the yarn to the needles as soon as it is fed while the others retain the elastic yarn and cause it to be held for several courses before being laid in to the fabric at one or more subsequent courses, and in wales (i. e., by needles) different from those at which it was previously laid in.

The wales in which the elastic yarns are laid 55

or tied in may be grouped in any convenient relationship round the fabric tube. Thus, they may be of two kinds, one kind having laying-in points at its intersections with one of the helical courses, and the other at the intersections with another. By disposing the wales of the two kinds alternately round the fabric, and disposing the helical courses with which the two kinds of wale intersect to form laying-in points alternately along the length of the fabric (separated by courses in which no laying-in is done), the elastic yarn may be drawn in a simple zig-zag, extending from one course over several courses to another and back, and being laid in at each turning point. By feeding elastic yarn in each course in which laying in occurs, the laying in of a new yarn for the first time is effected simultaneously with the laying in of an old yarn for the last time, so that the different elastic yarns meet, and the successive zig-zags form a pattern of diamonds or lozenges. Alternatively, pairs of wales of one kind may alternate round the fabric with pairs of wales, or single wales of the other. By these means the elastic yarn may be laid in in other forms than a simple zig-zag, e. g., so as to produce hexagonal figures. Again, the elastic yarn may be laid in at a third kind of wale, alternating with the wales or pairs of wales of the other two kinds, and in courses intermediate between those in which it is laid in at the other two kinds of wales. By these means the production of long floats of elastic yarn on the back of the fabric may be more readily avoided. At this third kind of course, the elastic yarn will cross the course, which does not occur at the other two kinds of course. Each elastic yarn may be completely laid in before the next elastic yarn is laid in. It is preferable, however, as indicated above, that the last laying in of each elastic yarn should take place simultaneously with, and in the same course as the first laying in of a new elastic yarn so that the fabric produced may be elastic throughout.

It is preferable that the elastic thread should be fed and laid in under a substantial tension, sufficient in itself to bring it to the desired condition of elongation. However, elastic yarns of the kind that are held in an extended condition by means of a gum or size may be employed under a lower tension, provided that the lower tension under which they are fed is carefully regulated to ensure their being laid in.

The fabrics produced in accordance with the present invention are particularly suitable for

the production of bathing costumes. For this purpose the elasticity in both directions enables the fabric to adapt itself closely to the figure of the wearer, so that the costume may be made without elaborate shaping being necessary in the cutting of the garment.

By way of example some forms of the fabric according to the present invention will now be described in greater detail with reference to the accompanying diagrammatic drawing, in which

Fig. 1 is a diagrammatic view of the fabric produced according to the invention showing the relative configuration of ground thread and elastic thread;

Fig. 2 is a view showing on a smaller scale the general arrangement of the elastic thread of the fabric illustrated in Fig. 1;

Fig. 3 is a modification of Fig. 2;

Figs. 4 and 5 show two modifications of details of Fig. 1;

Fig. 6 is a view similar to Figs. 2 and 3 showing another layout of the elastic threads.

Fig. 7 shows yet another layout of elastic thread in a fabric in accordance with the invention.

One form of fabric produced in accordance with the invention is shown in Fig. 1 in which the ground threads are indicated by the reference numerals 1 to 12 and the elastic threads, which enter the fabric along with ground threads 1 and 7 respectively, are indicated by the reference numerals 13, 14. The fabric is one knitted on a twelve-feeder machine, so that it has twelve helical courses formed by the twelve ground threads respectively. At the point 15 near the bottom of the figure are the two elastic threads 13, 14 associated with the head 16 of the loop in the thread 12, the thread preceding the thread 1 with which the elastic thread 13 enters the fabric. The threads 13 and 14 are not drawn with the thread 1 through the loop 16 of the thread 12, but slip down and become associated with that loop, so that the two portions 17 of the thread pass over the threads 13 and 14 on each side of the point 15, just as they pass over the thread 12 on each side of the head of the loop 16. In this way the elastic threads 13 and 14 are firmly attached in the fabric. Similarly in connection with the ground thread 4, the thread 13, having crossed behind the ground threads 1, 2 and 3 is associated at the point 18 in Fig. 1 with the head 19 of the thread 3 and are crossed by the portions 20 of the thread. After being laid in at the points 18, the elastic thread 13 is drawn further up the fabric, crossing behind the ground threads 4, 5 and 6, and is finally laid in at the points 21 near the left and right margins of Fig. 1, being here associated again with the thread 14 introduced into the fabric with the ground thread 7. The loop formation at these points is the same as that of the point 15 at the bottom of Fig. 1, except that the threads 13 and 14 have changed places, the thread 14 being laid in as newly introduced and the thread 13 being finally laid in. The thread 14 is laid in intermediately at the points 22 in the upper half of Fig. 1, and finally laid in at the point 23 at the top of the figure, which is in all respects similar to the point 15 at the bottom of the figure. Precisely similar effects to those produced at the points 15, 18, 21, 22 and 23 in Fig. 1 are produced all over the fabric.

It will be understood that the path of the elastic thread shown in Fig. 1 is only diagram-

matic and, by reason of the stiffness of the relatively thick elastic threads 13 and 14, the kink shown at the points 18 and 22 will not occur in practice, since these threads will force the ground threads out of shape.

In the result the general configuration of the elastic threads 13 and 14 in the finished fabric will be as is shown in Fig. 2 in which a flat diamond pattern is shown. The pattern shown in Fig. 2 is produced by a symmetrical and uniform arrangement of the wales in which the elastic threads 13 and 14 are laid in. It will be evident, however, that by an unsymmetrical arrangement many variations such as that shown in Fig. 3 may be produced. In Fig. 3 the wales in which the elastic threads 13 and 14 are laid in initially or finally (as at 15 in Fig. 1) are separated by different numbers of wales alternately so as to produce a distorted diamond effect. It may be convenient in this case to omit the intermediate laying in (as at 18 and 22 in Fig. 2) in the short sides 24 of the distorted diamonds while retaining them in the long sides 25 so that the elastic thread is laid into the fabric in the middle of the longer sides 25 only.

In the form of the invention described above the elastic thread is secured, at each point of laying in by thread springing from a single loop of ground thread, e. g., the portions 17 at the point 15 in Fig. 1. As a result the portions 17 of the ground thread which retain the elastic thread are very close together. In order to ease the strain on that stitch in the thread 1 which lies between the two portions 17 thereof the elastic thread may be secured by portions of thread springing from different loops, instead of from the same loop. The result is shown in the detailed Fig. 4 in which it will be seen that adjacent two loops 27, 28 of the thread 1 occur between the points 29 of the thread 1 which tie in the elastic threads 13 and 14. In this way the strain on the thread 1 may be considerably eased if desired. The principle may be carried further in the manner shown in Fig. 5 by employing instead of adjacent loops 27, 28, separate loops 30, 31, spaced apart by several intermediate loops in the thread 1 and by these means, as shown in Fig. 5, a long float 32 of each of the threads 13, 14 may be formed between the portions 33 of the thread 1 by which the elastic threads 13 and 14 are tied in.

The form of fabric produced by a conformation of loops of the kind shown in Fig. 5 is shown in Fig. 6 which is a figure similar in nature to Figs. 2 and 3. It will be seen that the elastic threads 13 and 14 form an open hexagonal pattern, being tied in to the fabric midway along each sloping side 35 and being tied in at each end of each horizontal side 36 at the points 37. Fig. 7 is similar to Fig. 6 but shows an arrangement in which both the expedients illustrated in Figs. 4 and 5 are employed. Thus, the wales in which the elastic threads are initially and finally laid in alternate in pairs, each pair forming the ends of the horizontal floats 38 and 39. Between the pairs are disposed single wales in which the elastic threads are intermediately laid in, as at 18 and 22 in Fig. 1. Here, again, the wales in which initial and final laying in occur alternate in pairs, the pairs being adjacent pairs in one case, forming very short floats 38 as shown in Fig. 4, and being separated in the other case to form long floats 39 as at 32 in Fig. 5. Between the pairs there

may be single wales in which intermediate laying in, as at 18 and 22 in Fig. 1, is effected. The resulting pattern, as shown in Fig. 7, is a pattern of alternating hexagons and diamonds.

Having described our invention what we desire to secure by Letters Patent is:

1. A circular knit elastic fabric comprising a plurality of inelastic yarns knitted into loops to form wales and continuous helical courses, and at least one elastic yarn laid into the fabric at the intersections of selected wales with one of said courses and laid into the fabric at the intersections of other selected wales with another of said courses spaced from the first, the parts of said elastic yarn lying between said courses, besides proceeding always in the same direction circumferentially of the fabric, extending always in one direction longitudinally of the fabric from one of said courses and always in the other direction from the other of said courses.

2. A circular knit elastic fabric comprising a plurality of inelastic yarns knitted into loops to form wales and continuous helical courses, and a plurality of elastic yarns, each laid into the fabric at the intersections of selected wales with one of said courses and laid into the fabric at the intersections of other selected wales with another of said courses spaced from the first, the parts of said elastic yarn lying between said courses, besides proceeding always in the same direction circumferentially of the fabric, extending always in one direction longitudinally of the fabric from one of said courses and always in the other direction from the other of said courses, two elastic yarns being laid in at each of said intersections, one extending in one direction from the course containing said intersection, and the other extending in the other direction.

3. A circular knit elastic fabric comprising a plurality of inelastic yarns knitted into loops to form wales and continuous helical courses, and at least one elastic yarn laid into the fabric at the intersections of selected wales with one of said courses and laid into the fabric at the intersections of other selected wales with another of said courses spaced from the first, the parts of said elastic yarn lying between said courses, besides proceeding always in the same direction circumferentially of the fabric, extending always in one direction longitudinally of the fabric from one of said courses and always in the other direction from the other of said courses, said elastic yarn being also laid into the fabric in at least one further course, spaced from any other course at which it is laid into the fabric, in yet other wales of the fabric.

4. A circular knit elastic fabric comprising a plurality of inelastic yarns knitted into loops to form wales and continuous helical courses, and a plurality of elastic yarns, each laid into the fabric at the intersections of selected wales with one of said courses and laid into the fabric at the intersections of other selected wales with another of said courses spaced from the first, the parts of said elastic yarn lying between said courses, besides proceeding always in the same direction circumferentially of the fabric, extending always in one direction longitudinally of the fabric from one of said courses and always in the other direction from the other of said courses, two elastic yarns being laid in at each of said intersections, one extending in one direction from the course containing said intersection, and the other extending in the other direction, each of said elastic yarns being also laid into the fabric in at

least one further course, spaced from any other course at which it is laid into the fabric, and in yet other wales of the fabric.

5. A circular knit elastic fabric comprising a plurality of inelastic yarns knitted into loops to form wales and continuous helical courses, and at least one elastic yarn laid into the fabric at the intersections of a set of selected wales with one of said courses, and laid into the fabric at 10 the intersections of a set of other selected wales with another of said courses spaced from the first, the wales of said two sets of wales occurring alternately round the fabric, the parts of said elastic yarn lying between said courses, besides 15 proceeding always in the same direction circumferentially of the fabric, extending always in one direction longitudinally of the fabric from one of said courses and always in the other direction from the other of said courses.

20 6. A circular knit elastic fabric comprising a plurality of inelastic yarns knitted into loops to form wales and continuous helical courses, and at least one elastic yarn laid into the fabric at the intersections of a set of selected wales with one of said courses, and laid into the fabric at 25 the intersections of a set of other selected wales with another of said courses spaced from the first, the wales of said two sets of wales occurring as pairs from one set alternating with pairs from the other set round the fabric, the parts of said 30 elastic yarn lying between said courses, besides proceeding always in the same direction circumferentially of the fabric, extending always in one direction longitudinally of the fabric from one of said courses and always in the other direction from the other of said courses.

35 7. A circular knit elastic fabric comprising a plurality of inelastic yarns knitted into loops to form wales and continuous helical courses, and 40 at least one elastic yarn laid into the fabric at the intersections of a set of selected wales with one of said courses, and laid into the fabric at the intersections of a set of other selected wales with another of said courses spaced from the first, the wales of said two sets of wales occurring 45 as pairs from one set alternating with single wales from the other set round the fabric, the parts of said elastic yarn lying between said courses, besides proceeding always in the same direction circumferentially of the fabric, extending 50 always in one direction longitudinally of the fabric from one of said courses and always in the other direction from the other of said courses.

55 8. A circular knit elastic fabric comprising a plurality of inelastic yarns knitted into loops to form wales and continuous helical courses, and a plurality of elastic yarns, each laid into the fabric at the intersections of a set of selected wales with one of said courses and laid into the fabric at the intersections of a set of other selected wales with another of said courses spaced from the first, the wales of said two sets of wales occurring alternately round the fabric, the parts of said elastic yarn lying between said courses, besides proceeding 60 always in the same direction circumferentially of the fabric, extending always in one direction longitudinally of the fabric from one of said courses and always in the other direction from the other of said courses, two elastic 65 yarns being laid in at each of said intersections, one extending in one direction from the course containing said intersection, and the other extending in the other direction, each of said elastic yarns being also laid into the fabric in at 70 least one further course, spaced from any other

course at which it is laid into the fabric, and in yet other wales of the fabric.

9. A circular knit elastic fabric comprising a plurality of inelastic yarns knitted into loops to form wales and continuous helical courses, and a plurality of elastic yarns, each laid into the fabric at the intersections of a set of selected wales with one of said courses and laid into the fabric at the intersections of a set of other selected wales with another of said courses spaced from the first, the wales of said two sets of wales occurring as pairs from one set alternating with pairs from the other set round the fabric, the parts of said elastic yarn lying between said courses, besides proceeding always in the same direction circumferentially of the fabric, extending always in one direction longitudinally of the fabric from one of said courses and always in the other direction from the other of said courses, two elastic yarns being laid in at each of said intersections, one extending in one direction from the course containing said intersection, and the other extending in the other direction, each of said elastic yarns being also laid into the fabric in at least one further course, spaced from any other course at which it is laid into the fabric, and in yet other wales of the fabric.

10. A circular knit elastic fabric comprising a

5 plurality of inelastic yarns knitted into loops to form wales and continuous helical courses, and a plurality of elastic yarns, each laid into the fabric at the intersections of a set of selected wales with one of said courses and laid into the fabric at the intersections of a set of other selected wales with another of said courses spaced from the first, the wales of said two sets of wales occurring as pairs from one set alternating 10 with single wales from the other set round the fabric, the parts of said elastic yarn lying between said courses, besides proceeding always in the same direction circumferentially of the fabric, extending always in one direction longitudinally of the fabric from one of said courses and always in the other direction from the other of said courses, two elastic yarns being laid in at each 15 of said intersections, one extending in one direction from the course containing said intersection, and the other extending in the other direction, each of said elastic yarns being also laid into the fabric in at least one further course, spaced from any other course at which it is laid into the fabric, and in yet other wales of the fabric.
